UNITED STATES PATENT OFFICE.

LE ROY H. RAND, OF BROOKLYN, NEW YORK.

METHOD OF MANUFACTURING DRESS-SHIELDS.

1,322,614.

Specification of Letters Patent. Patented Nov. 25, 1919.

Application filed March 22, 1919. Serial No. 284,344.

To all whom it may concern:

Be it known that I, LE ROY H. RAND, a citizen of the United States, and resident of New York city, borough of Brooklyn, 5 county of Kings, State of New York, have invented certain new and useful Improvements in Methods of Manufacturing Dress-Shields, of which the following is a full, clear, and exact description.

10 Among the principal objects which the present invention has in view are: to reduce the cost of manufacture of shields of the character mentioned; to shorten the time factor in the manufacture of said shields; 15 and to improve the structure of said shields.

Drawings.

Figure 1 is a view showing the two pieces of a dress shield overlaid, one independent 20 of the other, in the position in which they are placed prior to turning the connecting seam.

Fig. 2 is a diagram showing the operating table on which the shield members are held 25 during the operation of turning the seam, the two members of the shield being shown as originally disposed on the table, and as corresponding to the arrangement shown in Fig. 1.

30 Fig. 3 shows the method employed for lifting the flap of the seam or the operation succeeding the operation shown in the previous figure.

Fig. 4 shows the step in the method for 35 overturning the flap, such being the step in the operation succeeding that shown in the previous figure.

Fig. 5 shows the arrangement of the various members during the compression of the 40 overlaid flap of the body of the shield.

Fig. 6 is a view of the completed shield.

Description.

Heretofore, in the manufacture of dress 45 shields, the flap which forms the seam has been, of necessity, turned by hand. After the flap is turned, the seam has been completed by rolling the flap down upon the body of the shield which has previously 50 been provided with a suitable cement. The two pieces from which the shield has been constructed have been, and are at present cut by means of a suitable die.

When constructing shields in conformity 55 with the above described method, it is neces-

sary to exercise great care to prevent wrinkling and crumpling of the seam. This consumes time and requires a great amount of hand labor where the production is large.

When constructing shields in conformity 60 with the herein described method, it is found expedient and beneficial to the product to turn the flap 10, of the piece 11, which in conjunction with the piece 12, forms the shield. The flap 10 is lifted bodily, and in 65 one operation, from the position shown in Figs. 1 and 2 of the drawings, to the position shown in Fig. 3 of the drawings, a curved blade or plunger 13 being employed for this purpose. The plunger 13 conforms 70 to the edge of a table or plate 14, upon which normally is held a clamp plate 15. The plate 15 closes upon the two pieces 11 and 12, and is contiguous with the curved edge of the piece 12. When the flap 10 is raised to 75 the position shown in Fig. 3, it is disposed in the path of a plunger 16. The plunger 16 is then moved forward, the movement of such plunger being coincident with the withdrawal of the plunger 13. The plunger 16, 80 and the plunger 13 are disposed in the position indicated in Fig. 4 of the drawings. When the parts are so disposed, it will be noted, the flap 10 is loosely overlaid on the piece 12 and over the cemented area 85 thereof. The plunger 16 is then depressed on the flap 10, pressing the same on the pieces 11 and 12. When the pressure has been applied sufficiently long, the plunger 16 is raised and retracted to the position shown 90 in Fig. 2 of the drawings. The blank 15 is then lifted and the completed shield is removed from the plate 14.

From the foregoing, it will be seen that the seam formed by the flap 10 is smooth and 95 free of wrinkles or other imperfections, the material having been constantly controlled from the time that the blank 15 started to lift the flap 10. When the flap 10 is overlaid, the edge thereof is stretched slightly, 100 due to the fact that the raw edge of the flap 10, as originally formed, is converted from an inner curved edge to an outer curved edge, or in other words, the edge of the flap is slightly stretched or held under tension. 105

It is obvious that the width of the seam as formed with the flap 10 is of a more uniform dimension than if laid in place by the rolling process above indicated. Also, it is evident that the time required for the manufacture 110

of shields, and therefore the quantity of shields which may be turned out, is greatly amplified.

Claims.

- 5 1. The method of manufacturing dress shields consisting in producing component sheets of material for forming a shield, said parts having a curved edge for forming the 10 arm-hole portion of the shield, one of said sheets being slightly longer than the other of said sheets; then preparing the edges of said sheets with a suitable adhesive; then superposing said sheets so that the curved edge of 15 the longer of said sheets extends beyond the curved edge of the shorter of said sheets; then up-turning the entire curved edge of the longer sheet in the single and same operation; then over-turning the entire up-turned 20 edge on the edge of the short sheet in the same and single operation; then pressing the entire lapped edges by a single operation.

2. The method of manufacturing dress shields consisting in producing sheets of dress shield material coöperatively shaped in paired relation to form parallel curved edges for constructing the arm-hole seam of the shield, one of said sheets being longer than the other for being over-turned there-upon; then preparing the edge of the longer 25 of said sheets for adhesively uniting it to the shorter of said sheets; then clamping said sheets immovably and at the edge of the shorter of said sheets by a clamp conforming with said edge of the shorter sheet; then lifting simultaneously the entire length of the edge of said longer sheets having adhesive applied thereto, said edge being lifted to a position perpendicular to the body of said sheets; then retracting the member pressing 30 the superposed sheets; then pressing the entire length of said up-turned edge over upon the edge of said shorter sheet.

LE ROY H. RAND.
